UNITED STATES PATENT OFFICE

2,473,523

CONTAINER CLOSING APPARATUS

Edgar Henschen and Stanley W. Dennis, Baltimore, Md., assignors to Crown Cork & Seal Company, Inc., Baltimore, Md., a corporation of New York

Application January 24, 1947, Serial No. 723,986

16 Claims. (Cl. 226—83.1)

This invention relates to container closing apparatus of the type including a head by means of which closures are applied to containers as the result of the intermittent relative approach of the head and successive containers, and including means by which closures are transferred from a magazine to position for application between each closing action. An object of the invention is to provide improved and simplified closure transfer means including a reciprocating slide which, in the specific embodiment to be herein-after described, (1) provides at all times, in the operation of the apparatus, a support for a stack of closures, (2) in one direction of movement separates the lowermost closure from the stack, (3) in the other direction of movement transfers the separated closure to closure applying position, and (4) supports the closure in this position for application. Another object of the invention is to provide a closure applying head including built-in compensating means for over-height containers. Another object is to provide an improved drive for the slide whereby any tendency of the latter to bind in its guide due to transverse cocking is eliminated.

The above and other objects are attained in the apparatus shown by way of example in the accompanying drawings, this apparatus being particularly designed for the application of caps of the form shown in the copending application of Stanley W. Dennis, filed January 22, 1947, Serial No. 723,630. In the drawings,

Figure 1 is an end elevation of a capping head embodying the invention,

Figure 2 is a section substantially on line 2—2 of Figure 1,

Figure 3 is a side elevation of the head as seen from the right of Figure 1,

Figure 4 is a section substantially on line 4—4 of Figure 2,

Figure 5 is a view like that of Figure 4 showing the parts in a different relation,

Figure 6 is a section substantially on line 6—6 of Figure 5,

Figure 7 is a partial view like that of Figure 6 showing the parts in a different relation,

Figure 8 is an axial section of the transfer slide alone,

Figure 9 is a section substantially on line 9—9 of Figure 6, and

Figures 10, 11 and 12 are sections 10—10, 11—11 and 12—12, respectively, of Figure 4.

Referring first to Figures 1 to 3, reference numeral 15 designates generally a capping head which includes a bracket 16, in the form of a

5 cylinder, provided with upper and lower sets of laterally projecting ears 17, 18, 19, 20, by means of which the head is supportable on a turret such as is disclosed in the patent to Stewart and Franz, No. 2,311,786 of February 23, 1943, the bracket having a front sector removed to provide an opening 21 bounded top and bottom by horizontal walls 22 and 23 and by vertical side walls 24 and 25. A sleeve 26 is slidable in the lower part of 10 the bracket and is normally supported from the latter by means of abutting shoulders 27 and 28 on the bracket and sleeve respectively. Secured to the upper outer portion of the sleeve is a transverse block 29 which engages the vertical edges 15 24 and 25 of the bracket to prevent relative turning of the sleeve, and projecting oppositely from block 29 are aligned pins 30 and 31, Figures 2 and 3. Near its upper end, sleeve 26 has an internal annular flange 32 and below the latter 20 is provided with a pair of diametrically opposite axially extending grooves of which one appears at 33, Figure 2.

Reference numeral 34 generally designates a 25 throat carrier including a stem 35 having a lower portion 36 slidably received in sleeve 26 and prevented from rotation by splines as at 37 in the ways as at 33. Stem portion 36 terminates upwardly in an annular shoulder 38 and is surmounted by a coaxial reduced portion 39 whose upper end is slidable in the sleeve portion 40' of a cap 40 secured to the top of the bracket cylinder and constituting a part of the bracket. The upper projecting extremity of stem portion 39 carries a roller for the purpose disclosed in the 30 above-mentioned Stewart and Franz patent. A heavy compression spring 41 surrounds the stem and bears against flange 32 and cap 40, and a relatively weak compression spring 42 within spring 41 bears against shoulder 38 and the lower 40 end of sleeve portion 40'.

The carrier 34 includes a base block 43 integral, as here shown, with the stem 35 and providing a throat chamber 44 coaxial with the stem. Formed in the stem is a bore 45 coaxial with the 45 throat chamber and surmounted by a counter-bore 46 so that a shoulder 47 is provided. Outwardly of the throat chamber, there is formed in the block a downwardly tapering opening 48 whose outer wall is provided with a vertical slot 49. Fixed on the block in coaxial relation with opening 48 is a magazine cylinder 50, there being an annular shoulder 51 at the lower end of the magazine for the support of the package tube 52 for the caps to be applied. The cylinder has a 55 vertical slot 53 aligned with slot 49.

Pivoted on pins 30 and 31 are bell crank levers 54 and 55 having downwardly projecting arms 56 and 57 and forwardly projecting arms 58 and 59. Pivoted on inwardly projecting coaxial pins at the ends of arms 58 and 59 are rectangular blocks 60 and 61 slidable in horizontal tracks 62 and 63 defined between ribs 64, 65 and 66, 67 which project laterally from the cylinder 50.

Secured beneath block 43 is a platform 68 which provides a container guide aperture 69 comprising a cylindrical portion 70, coaxial with the throat chamber 44, surmounting a downwardly flared portion 71. The platform projects outwardly beyond the magazine to provide a slide-way comprising a depressed horizontal bottom wall 72 and parallel side walls 73 and 74. The bottom wall, which is provided with an elongated opening 75, extends up to the throat 70 while the side walls extend beyond the throat to terminate at recesses 76 and 77, Figures 4 and 5.

The transfer slide or injector member 78, as here shown, comprises a rectangular plate 79 of a thickness somewhat less than the height of side walls 73 and 74 and of a width for free sliding movement between the side walls. At its top, the rear, left-hand end portion of the plate is relieved to provide a cap supporting surface here shown as composed of two portions 80 and 81 separated, for the sake of reducing friction, by a longitudinally extending relief 82, the cap supporting surface being bounded by side walls 83 and 84 which converge symmetrically somewhat forwardly to a spacing slightly greater than the maximum diameter of the cap to be handled at vertical arcuate cutouts 85 and 86, the forward portion of the plate being cut away to provide extensions 87 and 88 and back somewhat beyond recesses 85 and 86 to provide an abutment wall 87.

Referring particularly to Figure 8, the lower inner edge of the extension 87 is rabbetted at 89 and rearwardly merges into an incline 90 which terminates in a transverse edge 91 at recess 85 to provide a blade generally designated at 92. Extension 88 is similarly formed to provide a blade 93 having a rearwardly directed edge 94. Beneath the blades the side walls of the extensions are parallel and are spaced apart a distance slightly greater than the diameter of the cap to be handled.

At its forward, right-hand end, plate 79 has its underside relieved to flushly receive a U-shaped plate 95 which is secured thereto by rivets as indicated in Figures 4 and 5. The arms 96 and 97 of plate 95 underlie the extensions 87 and 88 and have an inward projection about the same as that of blades 92, the spacing being sufficient to pass the head of the bottle to be capped. The inner edges of the arms merge in a circular line 98 which runs across the cross portion of plate 85, the cross portion extending somewhat forwardly of wall 87 as particularly shown in Figure 4. On top of their forward ends arms 96 and 97 carry stops 99 and 100 which are so arranged with respect to wall 87 as to provide three point centering means for the cap. As most clearly shown in Figure 11, the tops of the stops are spaced below the horizontal bottom walls of the blades 92 and 93.

Near its rear end, plate 78 is provided midway between its sides with an opening in which is fixed a downwardly projecting tubular stud 101 provided at its sides with openings as at 102 and 103 which are elongated fore and aft. Rotatably received in the stud is a cylindrical plug 104 hav-

ing a diametrical bore whose diameter is substantially the same as the height of the openings 102 and 103 and passed through all of the openings is a pin 105 which, through links 106 and 107, is in connection with the lower ends of arms 56 and 57 of the bell crank levers. The stud, through slots 102 and 103, supports the pin for limited free swinging about the stud axis and serves to guide the plug for rotary movement. The pin is closely received in the plug bore, and its movement is transmitted through the plug to the stud and thence to the slide.

An annular disc 108 is held against the top of throat chamber 44, Figure 2, by means of a ring 109 which is supported by the platform, the ring having at its upper end an internal rabbet in which is received the out-turned ends of the segments 110 of an expandible throat 111, the segments being normally maintained in constricted relation by a surrounding coil spring 112. Slidable in bore 45 is a tubular presser foot carrier 113 reduced at its lower end to provide a shoulder engageable with the inwardly projecting margin of disc 108 to positively limit downward movement of the carrier. Near its upper end the carrier is internally enlarged to provide a seat for a washer 114 against which bears the lower end of a compression spring 115 whose upper end seats against the top of counterbore 46, the strength of spring 115 being intermediate that of springs 41 and 42. Reference numeral 116 designates the presser foot which is provided on its upper side with a spherical boss 117 engaging the mating end of carrier 113. Projecting upwardly from the boss is a screw 118 and between the head of the latter and an internal shoulder of carrier 113 is a volute spring 119 which seats the boss against carrier 113 so that the presser foot is normally horizontal but can be tilted somewhat in any direction.

In Figure 2 the parts are in normal or rest position. Sleeve 26 is held in its lowermost position by spring 41 and the throat carrier is pressed to its lowermost position by spring 42. Downward movement of the throat carrier, together with the magazine, has swung the bell crank levers counter-clockwise to advance the slide to the position shown wherein stud 101 abuts portion 68' of the platform and so limits the action of spring 42. The presser foot is urged to its lowermost position by spring 115.

The cap of the said Dennis application, shown at 120 in Figures 6 and 7, has a skirt 121 depending from a circular top and terminating in a corrugated peripheral flange 122, the skirt being slightly shouldered at 123 to prevent tight nesting. In Figures 2 and 6, the bottom cap of the stack rests on the slide surface 80, 81 and another cap is supported by the ledges 96 and 97 below the throat and with its top surface spaced below the presser foot a distance slightly greater than the height of stops 99 and 100. If, as in the Stewart and Franz patent above-mentioned, a bottle is elevated through the centering aperture 69, it will engage the cap to be applied and will lift the cap against the presser foot so that its flange is just above the stops 99 and 100 and just below the blades, the spaces between the stops and the bottom surfaces of the blades being somewhat greater than the total thickness of the flange. Consequently, as the elevation of the bottle continues, the bell crank levers are swung clockwise and the slide is retracted with the cap flange being cleared through the spaces between the stops and blades. The presser foot does not move rela-

tive to the throat carrier at this time because spring 115 is sufficiently heavier than spring 42 so that the latter alone will yield. However when the top of base block 43 strikes the lower end of sleeve 26, the rise of the throat carrier will stop and spring 115, being much weaker than spring 41, will permit the presser foot to rise, and when the top of carrier 113 strikes shoulder 47 the capping operation, in the case of a bottle of normal height, is completed. If the bottle is over-height, however, spring 41 will yield and thus compensate for the discrepancy. It would not be possible to compensate for extra bottle height by increasing the range of upward movement of carrier 113 in bore 45 since, in that case, the greater projection of the bottle top in the throat could result in damage to the bottle, particularly where the bottle has an external finish ring just below the bead.

As the slide was retracted, the blades sliced off the lowermost cap from the stack and the latter was deflected by the blade inclines onto the ledge provided by plate 95, the cap being centered by wall 87 and stops 99 and 100 and the support of the stack being taken over by the blades 92 and 93 as indicated in Figure 7. The slicing action occurs by reason of the fact that the blade edges 91 and 94 are spaced above surface 80, 81 a distance slightly greater than the thickness of the cap flange and so take over the latter as the slide is retracted. The wedge shaped blades effect positive separation. After the capped bottle is lowered, the throat carrier is lowered by spring 42 and the slide advances to carry the separated cap beneath the throat in substantially centered relation thereto, overthrow of the cap being prevented by stops 99 and 100. The stack now again rests on the surface 80, 81.

Thus, the single slide eliminates a number of parts heretofore necessary in apparatus of this type. For example, in the prior art, as exemplified in the patent to Huntley and Rau, No. 1,956,218 of April 24, 1934, the stack is supported and fed from by means of a number of oscillable members, requiring a special drive, at the base of the magazine, and the slide merely propels the cap to a position beneath the throat where it is supported by means of a special ledge. The compensating feature makes unnecessary the provision of a yieldingly supported cradle cam for the bottle supporting chucks as in the hereinbefore mentioned Stewart and Franz patent. Due to the drive of the slide through the swiveling cross pin, twisting effects and any tendency to jam caused thereby, are eliminated.

It will be understood that the disclosure herein is intended as illustrative and that under the claims which follow, changes in the form and arrangement of parts, as, for example, for the handling of different types of closures, are contemplated. Furthermore, while the Stewart and Franz Patent No. 2,311,786 has been referred to and adopted herein as disclosing a system in which the apparatus of the present invention is well adapted for use, it will be understood that this is not intended as limiting since the invention is equally applicable in other arrangements, wherein, for example, the head may be lowered instead of the container lifted.

We claim:

1. In apparatus for applying closures to containers, the closures each comprising a circumferential flange, said apparatus including a head comprising a vertical magazine for receiving a stack of the closures and a vertical throat

horizontally spaced from the magazine, guide means extending between the lower ends of said magazine and throat, a slide reciprocable in said guide means between retracted and advanced positions, said slide comprising a rear portion which provides a supporting surface for the stack when the slide is in advanced position, a pair of spaced parallel forward extensions having surfaces adapted to support a closure through its flange, said extensions having free forward ends with the space therebetween unobstructed, whereby the extensions may be retracted from straddling relation with respect to a bottle neck, blade means carried by the extensions above the last mentioned surfaces for removing the lowermost closure from the stack and depositing it on said surfaces as the slide is retracted, an upwardly projecting abutment surface at the rear ends of said surfaces to retain the removed closure thereon for transportation to a position beneath said throat as the slide is advanced, and means operable upon relative vertical movement of said head and a container to be closed for reciprocating said slide between its limit positions.

2. Apparatus according to claim 1 wherein centering means including stops on the forward ends of said extension surfaces is provided, and wherein in the closing operation initial engagement of the closure and the container to be closed causes the release of the closure from said stops.

3. Apparatus according to claim 1 wherein a presser foot is provided in said throat and is normally spring-urged downwardly to a limit position wherein it is spaced above a closure as delivered by said extensions beneath said throat, wherein centering means including stops on the forward ends of said extensions is provided, and wherein in the closing operation initial engagement of the closure and container to be closed causes the release of the closure from said stops just before the closure and presser foot come into engagement.

4. In apparatus for applying closures to containers, the closures each comprising a circumferential flange, said apparatus including a head comprising a vertical magazine for receiving a stack of the closures and a vertical throat horizontally spaced from the magazine, guide means extending between the lower ends of said magazine and throat, a slide reciprocable in said guide means between retracted and advanced positions, said slide having a rear portion providing a supporting surface for the stack when the slide is in advanced position, said slide having at its forward end a pair of forwardly extending blades horizontally spaced apart somewhat less than the diameter of the closure and having rearwardly faced horizontal edges disposed in advance of said supporting surface and at a height above said surface slightly greater than the thickness of said flange whereby the blades act to separate the lowermost closure from the stack as the slide is retracted and to take over the support of the stack, means for reciprocating said slide, and means for delivering the separated closure beneath said throat.

5. In apparatus for applying closures to containers, the closures each comprising a circumferential flange, said apparatus including a head comprising a vertical magazine for receiving a stack of the closures and a vertical throat horizontally spaced from the magazine, guide means extending between the lower ends of said maga-

zine and throat, a slide reciprocable in said guide means between retracted and advanced positions, said slide having a rear portion providing a supporting surface for the stack when the slide is in advanced position, said slide having at its forward end a pair of forwardly extending blades horizontally spaced apart somewhat less than the diameter of the closure and having rearwardly faced horizontal edges disposed in advance of said supporting surface and at a height above said surface slightly greater than the thickness of said flange whereby the blades act to separate the lowermost closure from the stack as the slide is retracted and to take over the support of the stack, said slide including ledges beneath said blades adapted to receive said lowermost closure and also including an abutment portion serving to push the received closure into centered relation to the throat when the slide is advanced, and means operable to reciprocate said slide.

6. Apparatus according to claim 5 wherein stops are provided on top of said ledges at the forward ends thereof in position to engage the flange of a closure supported on said ledges so as to prevent overthrow of the closure as the slide reaches its advanced position, the tops of said stops being spaced below said blades so that upon initial relative vertical displacement of the closure and slide in the closing operation the slide can be retracted and the cap flange cleared through the spaces between said stops and blades.

7. Apparatus according to claim 5 wherein stops are provided on top of said ledges at the forward ends thereof in position to engage the flange of a closure supported on said ledges so as to prevent overthrow of the closure as the slide reaches its advanced position, the tops of said stops being spaced below said blades so that upon initial relative vertical displacement of the closure and slide in the closing operation the slide can be retracted and the cap flange cleared through the spaces between said stops and blades, and including a presser foot in said throat normally spring-urged downwardly to a limit position wherein it is spaced above a closure supported on said ledges beneath said throat and the closure at the end of said initial relative displacement.

8. An apparatus for applying closures to containers, the closures each comprising a top, a skirt and a radially extending circumferential flange at the bottom of the skirt, said apparatus comprising a vertical magazine for receiving a stack of closures, a vertical throat carrier horizontally spaced from and mounted for limited vertical movement with the magazine, a throat in said carrier, guide means extending between the lower ends of the magazine and throat, a slide reciprocable in said guide means having a rear portion providing a supporting surface for the stack when the slide is advanced toward the throat and having at its forward end a pair of forwardly extending blades provided with rearwardly faced horizontal edges beyond and above said supporting surface a height slightly greater than the thickness of the closure flange, whereby the blades act to separate the lowermost closures from the stack as the blade is retracted toward the magazine, said slide including ledges beneath said blades to receive said lowermost closure, said ledges having stops at their forward ends projecting upwardly toward but spaced from said blades to prevent overthrow of the closure as the slide reaches its advanced position, a spring urging the throat carrier and

magazine to a lower limit position, a presser foot in said throat having a lower limit position spaced slightly above a closure supported on said ledges, a second spring urging the foot to said lower limit position, whereby, when said closure is raised by a bottle to be capped into contact with the foot, the closure flange is horizontally aligned with the spaces between said stops and said blades, the first mentioned spring being weaker than the second spring, whereby continued upward movement of the bottle raises the throat carrier and magazine without relative movement between the foot and the throat, and means actuated by said upward movement of the magazine and throat carrier for retracting the slide, the closure flange passing through said spaces.

9. Capping apparatus comprising a bracket, a sleeve supported by said bracket for vertical movement, stop means on the bracket limiting downward movement of said sleeve, spring means between said bracket and sleeve normally holding said sleeve in its lower limit position, a throat carrier having a stem portion slidable in said sleeve, said carrier and sleeve having cooperating abutment portions limiting the upward travel of said stem portion relative to said sleeve, said stem portion having a vertical bore in its lower end, a presser foot carrier slidable in said bore, said carriers having cooperating abutment portions limiting the upward travel of the presser foot carrier relative to the throat carrier, spring means weaker than the first mentioned spring means urging the presser foot carrier downwardly, and stop means on the throat carrier limiting the downward movement of said presser foot carrier.

10. Apparatus according to claim 9 including still weaker spring means between said bracket and throat carrier and urging the latter downwardly.

11. Capping apparatus comprising a bracket, a sleeve vertically slidable in said bracket, stop means on the bracket limiting downward movement of said sleeve, a throat carrier having a stem portion slidable in said sleeve, said bracket including a bearing cap above said sleeve in which the upper part of said stem portion is slidably, a compression spring surrounding said stem portion between said cap and sleeve and normally holding the sleeve in its lower limit position, said carrier and sleeve having cooperating abutment portions limiting the upward travel of said stem portion relative to said sleeve, said stem portion having a vertical bore in its lower end, a presser foot carrier slidable in said bore, said carriers having cooperating abutment portions limiting the upward travel of the presser foot carrier relative to the throat carrier, a compression spring in said bore urging the presser foot carrier downwardly, and stop means on the throat carrier limiting the downward movement of the presser foot carrier.

12. Apparatus according to claim 11 including a still weaker compression spring surrounding said stem portion with its upper end against said cap, and a shoulder on said stem portion against which the lower end of the last-named spring bears.

13. In apparatus for applying closures to containers, a vertical magazine for receiving a stack of closures, a vertical throat horizontally spaced from the magazine, a slide and guide means therefor extending between the lower ends of the magazine and the throat, a stud projecting from one face of said slide substantially midway between the lateral edges thereof, a member con-

centric with said stud and guided for rotation thereby, a pin, said stud and member being transversely apertured to receive said pin with capability of swinging relative to the stud but not to said member, and operating arms engaging the ends of said pin.

14. In apparatus for applying closures to containers, a vertical magazine for receiving a stack of closures, a vertical throat horizontally spaced from the magazine, a slide and guide means therefor extending between the lower ends of the magazine and the throat, a hollow stud projecting from one face of said slide substantially midway between the lateral edges thereof, said stud having lateral openings elongated fore and aft, a 15 plug rotatable in said stud and having a diametrical round opening, a pin passing through said openings, and operating arms engaging the ends of said pin.

15. Apparatus according to claim 14 including a stop on said guide means engageable by said stud to limit movement of said slide in one direction.

16. Apparatus according to claim 9 including a vertical magazine supported by the throat car- 25

rier, a horizontal slide for transferring closures from the magazine to applying position, and slide actuating means comprising a pair of parallel bell crank levers pivotally supported by said sleeve on a horizontal axis, said levers having downwardly projecting arms in connection with said slide and outwardly projecting arms straddling said magazine and engaged therewith for swinging thereby as the throat carrier moves relative to said bracket.
